(57) **CLAIM**

The ornamental design for a construction toy with interlocking bricks as shown and described.

DESCRIPTION

FIG. 1 is a perspective view of a construction toy with interlocking bricks;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

Portions of the construction toy with interlocking bricks that are shown in broken lines are for the purpose of illustrating portions of the article that form no part of the claimed design.

1 Claim, 7 Drawing Sheets
